UNITED STATES PATENT OFFICE.

JOHN Q. SHERMAN, OF DAYTON, OHIO.

MANIFOLDING REGISTER.

Application filed February 3, 1921. Serial No. 442,254.

To all whom it may concern:

Be it known that I, JOHN Q. SHERMAN, a citizen of the United States, and resident of the city of Dayton, in the county of Montgomery and State of Ohio, have invented certain new and useful Improvements in Manifolding Registers, of which the following is a full, clear, and exact description, reference being had to the drawings forming part of this specification.

My invention relates to manifolding registers of the type, wherein a record strip and the desired number of strips to be issued from the machine are fed in perfect alignment, and uniformly to each other, over a writing table upon which impressions are duplicated for the various strips.

In the use of an alignment feed, such as, for example, a feed pin or pins which come into engagement with similarly located alignment apertures in the various webs, it is not proper practice to steadily withdraw one of the strips onto a rewind roll for purposes of a record, because the strain of the rewind roll on the record strip is counter to the strain of the webs of paper to be issued from the machine, the record strip being urged forward and the issuing strips tending to lag behind, these two opposite tendencies acting to interfere with the normal aligning action of the feed pins. Indeed, all webs being aligned should be free of any substantial pull in any direction while being aligned, and efforts to feed and align a full sized record slip have been unsuccessful in the past due to failure to understand this principle.

In earlier machines constructed by me, I have adopted one of two methods for avoiding pulling continuously on the record strip from the rewinding roll during aligning. Thus I either let the full amount of the record strip issue without interference along with the other strips, and then by a spring operated device drew it up on a rewind roll, or I drove the rewind roll from the common feeding device by means of a friction, and stopped the rewind roll or gripped the paper, so as to enforce an inhibition of the rewind during a portion of the common feed.

It is my object in the present construction to do neither of these two things, but instead to enforce on the record strip the necessity of passing over a retarding device, located intermediate the feed and the rewind, that

operates synchronously with the common feed so as to maintain a substantially uniform looseness of paper at all times intermediate the feed and the rewind.

Among other objects of my invention herein, are the provision of a feed handle stop, which operates by means of a slight twisting of the handle itself, thereby greatly simplifying the operation of such stop, and the provision of a modified frictional feeding device between the common feed mechanism and the rewind roll, said device being adjustable for tension.

These various objects and advantages I accomplish by that certain construction and arrangement of parts to be hereinafter more specifically pointed out and claimed.

In the drawings,

Figure 1 is a detail side elevation showing the mechanical parts of my new improvement.

Figure 2 is a detail elevation, showing in side elevation the friction device, with adjustable members thereof.

Figure 3 is a detail sectional view of the feed handle stop.

Figure 4 is a detail elevation of the pin socket, serving as the fixed member of the feed handle stop.

Referring first to the normal parts of a pin wheel feed manifolding register, which I have selected for purposes of illustrating my invention, it will be noted that the machine has a casing 1, a top 2, a feed shaft 3, and feed shaft crank 4, with handle 5. On the feed shaft are pin bearing members 6, bearing pins 7 which enter successive holes formed in the strips of paper to be fed through the machine. Ordinarily said holes will be formed marginally of the strips, which is normal practice in this form of machine.

On a pair of arms 8, one on each side of the casing, is a pressure roll 8^a, which, as is the usual practice, will be maintained in position of holding the paper against rising off of the pins, without exerting any frictional strain thereon. This roll may be under control of the usual cams, (not shown) which permit it to clamp down against the paper, at the conclusion of each feeding operation.

The paper passes over a tablet or writing table 9, which in this instance is extended to act as a stripper for the pins of the feeding device, suitable clearance slots be-

ing formed to permit the pins to protrude. The roll 8^a is also grooved for pin clearance in the usual manner.

The operation of feeding devices, such as have been briefly noted above, is to draw the webs of paper without exerting any grasp thereon except at the point of pin engagement with the marginal holes therein, in consequence of which the paper is free to adjust itself on the pins and keep in perfect alignment.

As in that type of machine shown in the application of Sherman and Metzner, Serial No. 299,793 filed May 26, 1919, now Patent No. 1,439,135, the feed shaft is equipped with a gear 10, which meshes with another gear 11, mounted on a stud 12 in the side of the machine. On this stud is also mounted a lever 13, which carries on one end a pinion 13^a, which stays in mesh with the gear 11 in all positions of the lever. A spring 14, adjustable over a series of pins 15 in the case, serves to maintain tension on this lever to throw the pinion toward frictional driving position, as will be noted.

The pinion carries along with it a friction wheel 16, which has a V-shaped periphery terminating in a rib 17.

When the feed shaft is revolved by means of the crank and handle, the friction wheel 16 is revolved.

The friction device and mounting for the rewind roll are of special construction in my present device, for permitting ready removal of the rewind roll, and for permitting an adjustable friction.

Thus, there is mounted in the side of the machine casing at an offset 18 therein, a stub shaft 19. On this stub shaft is slidably and rotatably mounted a half of a friction disk 20, having its inner face beveled off to correspond to the V-shaped side of the friction wheel 16. Another like disk 21, having its face beveled toward the first disk 20, is held rotatably on the said stub shaft by means of a screw 22. The two disks are tied together for joint operation by means of a pin 23 passing through the disk 21 and slidably engaging within the disk 20.

A spring 24, mounted over the stub shaft, bears against a washer 25 set against the outer face of the disk 20, and against another washer 26, which rests against the casing of the machine when in normal position.

Mounted, however, on a post 27 having a threaded end, is a wing nut 28 bearing against a disk 29 on said post. This disk carries a plurality of pins 30 which pass through holes in the offset of the casing and bear against the said washer 26. The adjusting of the wing nut, therefore, adjusts the spring tension against the friction disk 20, and presses it toward the matching disk 21.

It will be noted that the friction disk 16, driven by the common paper feed device, engages with its rib 17 between the two half disks 20 and 21, and said half disks are maintained in parallel with each other by means of an idler disk 31 which presents a like periphery between the disks, as that of the disk rib 17. The V-shaped portion of the disk 16 engages the beveled faces of the two disk members 20 and 21.

Thus the spring 24 controls the amount of frictional grasp between the disk 16 and the two half disks 20 and 21, and by a simple wing nut the tension of this spring may be readily adjusted.

The rewind roll has a spindle 32, on which is a suitable core 33, said core having a bar 34 thereon for engaging the paper at the start thereof. This spindle finds a suitable bearing at one end in the casing of the machine, as in ordinary practice and the other end is tapered, as at 35, and engages in a tapered hole 36 in the exposed face of the inner friction disk 21. A hole 37 in the core piece fits the pin 38 on the inner face of the disk 21, so that the core will be driven around by the operation of the friction.

The retarding device, which results in the formation of a looseness of the record strip at all times, on the feed pins, comprises a pinion 39 mounted on the casing, and meshing with the gear 11. This is on a shaft 39^a which carries a pair of pin wheels 40 having pins 41 thereon, said wheels and pin spacing and gear ratio being such that the pins will engage in the holes in the record strip, with the same timing as those of the common feed.

The record strip A coming from the common feed is passed over an idler 42, if desired and from there is passed over the feed pins 41. From these feed pins the strip passes preferably directly to the rewind roll. A roll or bar 8^b, preferably corresponding to the roll 8 is carried by the arms 8, and acts to keep the record strip down on the pins 41.

As so constructed, the retarding device acts as follows:—When the operator sets up the machine, he places the complete set of webs in alignment, and over the pins of the main feed. He then brings the record strip or web to the pin wheels 40, leaving a looseness or small loop 43 between the main feed and the smaller pin wheels. The end of the record strip, as soon as it is long enough, is brought down and engaged over the rewind roll.

When the operator moves the feed shaft thereafter, the wheels 40 act to maintain between the main feed pins and said wheels 40 a loop of uniform dimension at all times, and the rewind roll drags continually at the strip between the pin wheels 40 and said roll.

Since the friction is designed particularly for slippage before sufficient strain is set up to tear the paper, there will be a tight feeding on the rewind roll, without chance of 5 destroying the strip because of its being pulled tightly on the pins 41. The pins 41 will, however, keep the paper loose on the main feed pins, so that it can be aligned as well as fed.

10 In connection with the handle on the feed shaft crank, I have provided a special form of stop to bring all members to a positive stop at the end of each complete rotation of the feed shaft.

15 Thus on the casing of the machine is mounted a plate 44, having beveled sides and a central socket 45, to which leads a channel 46. The feed crank handle is made up of a central cylinder 47 threaded into the crank, 20 and carrying in a suitable socket therein a stop pin 48, under the influence of a spring 49, housed within the said socket. This pin has a small laterally extending pin 50 riding in a slot 51 in the cylinder.

25 The handle proper, as indicated at 5, fits over and is spaced away from the central cylinder, and is rotatably mounted on the outer end of the cylinder by means of a screw 52. At its inner end the hollow handle portion 5 is equipped with a ring of metal made up with a cam edge 53, which rides under the small pin 50.

Thus as the handle is given a slight turn, 35 with it the large pin toward the cam crest 54, but any further turning of the handle will permit the spring action behind the stop pin to return the said pin to normal position.

40 In operation beginning with the stop pin engaged in its socket 45, the operator imparts a slight revolution to the crank handle which elevates the stop pin and permits an operation of the crank. As the operation 45 proceeds and the operator maintains his grasp on the handle, he will inevitably revolve the said handle, thereby permitting the small pin to ride down on the cam surface and permit the stop pin to protrude 50 again, thereby riding through the guide channel in the plate 44, and dropping into the socket 45, at the close of a complete operation.

I desire to note of my description of the 55 rewind, alignment feed, and retarding mechanism, that this principle may well apply to other forms of alignment feed which employ the feed pins on the common feed mechanism for a portion only of the feed, or to other alignment feed devices, using a rewind, since to my knowledge no one has inserted a retarder which maintains a looseness of the record strip beyond the common feed mechanism, and rewinds the 60 said record strip from beyond the retarder.

Accordingly, I do not desire that my claims that follow be limited to the particular form of manifolding register which I have described above, since it is merely my preferred form, and one to which I have applied the device described with great success.

Having thus described my invention, what I claim as new and desire to secure by Letters Patent, is:—

1. In a manifolding register or the like, the combination of a feeding mechanism for feeding paper in a plurality of webs through said register, means for accumulating one of said webs within the machine 80 for a record, after it has been so fed, and means located between the feeding mechanism and the accumulating means for retarding the movement of said web to maintain a constant looseness of said web between said feeding mechanism and accumulating means at all times.

2. In a manifolding register or the like, the combination of a feeding mechanism for simultaneously feeding and aligning a plurality of webs of paper, means for accumulating for a record one of said webs of paper, and means located between the feeding mechanism and the accumulating means for enforcing a movement of the said web at 95 the same speed as the movement of the feeding mechanism at a point intermediate it and the accumulating means.

3. In a manifolding register or the like, the combination with a pin bearing body 100 adapted to engage in aligning apertures in a plurality of webs of paper, and feed in true alignment said webs, of means for accumulating one of said webs for a record, and means for enforcing a movement of the 105 said web at the same speed as the movement of the said pin bearing body located at a point intermediate said pin bearing body and the accumulating mechanism.

4. In a manifolding register or the like, 110 the combination with a pin bearing body adapted to engage in aligned apertures in a plurality of webs of paper, and feed in true alignment said webs, of means for accumulating one of said webs for a record, and means for enforcing a movement of the said web at the same speed as the movement of the 115 said pin bearing body located at a point intermediate said pin bearing body and the accumulating mechanism, said means comprising an additional pin bearing means driven synchronously with the pin bearing body.

5. In a manifolding register or the like, 120 the combination of a feeding mechanism for simultaneously feeding and aligning a plurality of webs of paper, means for accumulating for a record one of said webs of paper, and means for enforcing a movement 125 of the said web at the same speed as the 130

movement of the feeding mechanism at a point intermediate it and the accumulating means, said accumulating means comprising a rewind roll driven from the feeding mechanism.

6. In a manifolding register or the like, the combination of a feeding mechanism for simultaneously feeding and aligning a plurality of webs of paper, means for accumulating for a record one of said webs of paper, and means for enforcing a movement of the said web at the same speed as the movement of the feeding mechanism at a point intermediate it and the accumulating means, said accumulating means comprising a rewind roll driven frictionally from the feeding mechanism.

7. In a manifolding register or the like, the combination with a pin bearing body adapted to engage in aligned perforations in a plurality of webs of paper, and feed in true alignment said webs, of means for accumulating one of said webs for a record, and means for enforcing a movement of the said web at the same speed as the movement of the said pin bearing body located at a point intermediate said pin bearing body and the accumulating mechanism, said accumulating means comprising a rewind roll driven from the said pin bearing body.

8. In a manifolding register or the like, the combination of a feeding mechanism for feeding paper in a plurality of webs through said register, means for accumulating one of said webs within the machine for a record, after it has been so fed, and means for retarding the movement of said web to maintain a constant looseness of said web between said feeding mechanism and accumulating means at all times, said accumulating mechanism being frictionally driven from the feeding mechanism.

9. In a manifolding register or the like, the combination of a feeding mechanism for feeding paper in a plurality of webs through said register, means for accumulating one of said webs within the machine for a record, after it has been so fed, and means for retarding the movement of said web to maintain a constant looseness of said web between said feeding mechanism and accumulating means, said accumulating mechanism being frictionally driven from the feeding mechanism, and said retarding means comprising a member engaging said record web, and driven from the feeding means and at the same speed therewith.

10. In a manifolding register or the like, the combination with a pin bearing body adapted to engage in aligned apertures in a plurality of webs of paper, and feed in true alignment said webs, of means for accumulating one of said webs for a record, and means for enforcing a movement of the said web in time with the movement of the

said pin bearing body located at a point intermediate said pin bearing body and the accumulating mechanism, said accumulating means comprising a rewind roll driven from the pin bearing body with the intervention of a friction drive of a V-shaped periphery disk engaging between an inversely shaped member that engages said roll.

11. In combination with the paper feeding mechanism of a manifolding register, a friction disk driven thereby, a rewind roll for preserving as a record a strip fed by said paper feeding mechanism, and a plurality of friction members between which the disk lies one of them having driving connection with the rewind roll, and spring means for maintaining said members in engagement with said friction disk.

12. In combination with the paper feeding mechanism of a manifolding register, a friction disk having a V-shaped periphery driven by said mechanism, a rewind roll for preserving as a record a strip fed by the said mechanism, and means connected to the rewind roll and comprising disks spring pressed toward each other and having sides beveled to form a contact member with the V-shaped periphery of the friction disk.

13. In combination with the paper feeding mechanism of a manifolding register, a friction disk having a V-shaped periphery driven by said mechanism, a rewind roll for preserving as a record a strip fed by the said mechanism, and means connected to the rewind roll and comprising disks spring pressed toward each other and having sides beveled to form a contact member with the V-shaped periphery of the friction disk, said friction disk having a peripheral rib and said rib being positioned to engage between said spring pressed disks.

14. In combination with the paper feeding mechanism of a manifolding register, a friction disk having a V-shaped periphery driven by said mechanism, a rewind roll for preserving as a record a strip fed by the said mechanism, and means connected to the rewind roll and comprising disks spring pressed toward each other and having sides beveled to form a contact member with the V-shaped periphery of the friction disk, and means for adjusting the spring tension of the said spring pressed disks.

15. A rewind mechanism for a manifolding register or the like, comprising in combination, a direct driven friction disk, a pair of disks spring pressed toward each other, said friction disk being resiliently urged to a position of engagement between said spring pressed disks, a rewind roll and driving connection between the spring pressed disks and the said rewind roll.

16. A rewind mechanism for a manifolding register or the like, comprising in combination, a direct driven friction disk, a

- pair of disks spring pressed toward each other, said friction disk being resiliently urged to a position of engagement between said spring pressed disks, a rewind roll and driving connection between the spring pressed disks and the said rewind roll, and means for adjusting the spring tension of said spring pressed disks. 5
17. A rewind mechanism for a manifold-
10 ing register or the like, comprising in combination, a direct driven friction disk, a pair of disks spring pressed toward each other, said friction disk being resiliently urged to a position of engagement between
15 said spring pressed disks, a rewind roll and driving connection between the spring pressed disks and the said rewind roll, said friction disk having V-shaped periphery terminating in a rib, and said spring pressed
20 disks adapted to engage over the said rib, and beveled to present a V-shaped channel to the V-shaped periphery of the said friction disk. 25
18. In a manifolding register, a paper feed, a gear driven from the paper feed, a planetary pinion movable around said gear and meshing therewith, means for resiliently urging said pinion in one direction, a rewind roll, a pair of friction disks connected
30 to the rewind roll, and resiliently urged toward each other, said pinion carrying a friction disk adapted under the resilient urge of the pinion to engage between said pair of friction disks, and means for adjusting the resilient urge of said pair of friction disks toward each other. 35
19. In a machine of the character described, the combination with a feed driven disk, a stud mounted on the machine, a pair
40 of disks on said stud rotatably mounted, and slidably relatively to each other, a spring on the stud, pressing said disks together, means carried on the machine for adjusting the tension of said spring, said feed driven
45 disks being adapted to engage between said pair of disks, a rewind roll and spindle therefor, means for mounting said spindle demountably within the end of said stud, and means on one of the pair of disks for
50 detachably engaging the rewind roll, as and for the purpose described. 55
20. In a manifolding register, the combination of a paper feeding and rewind device, comprising a rotary pin bearing element, having pins thereon for engaging in successive holes formed in the paper to be fed, a gear driven from said rotary pin bearing element, a rewind for one of said
strips of paper fed by the pin bearing element, driven from said gear, and an additional pin bearing element driven from said gear, and located intermediate the rewind and the pin bearing element first mentioned. 60
21. In a manifolding register, the combination of a paper feeding and rewind device, comprising a rotary pin bearing element, having pins thereon for engaging in successive holes formed in the paper to be fed, a gear driven from said rotary pin bearing element, a rewind for one of said
strips of paper fed by the pin bearing element, driven from said gear, and an additional pin bearing element driven from said gear and located intermediate the rewind and the pin bearing element first mentioned, 65
a roll or bar for each pin bearing element, and arms carrying both rolls or bars, and retaining them in position adjacent their respective elements, to maintain the paper in loose engagement with the pins thereon. 70
22. In combination with the paper feeding mechanism of a manifolding register, a friction disk driven by said mechanism, a rewind roll for preserving as a record, a strip fed by the said feeding mechanism, and means connected to the rewind roll and comprising disks pressed toward each other, and having sides adapted to form contact members with the friction disk above mentioned. 75
23. In combination with the paper feeding mechanism of a manifolding register, a friction disk driven by said mechanism, a rewind roll for preserving as a record, a strip fed by the said feeding mechanism, and means connected to the rewind roll and comprising disks pressed toward each other, and having sides adapted to form contact members with the friction disk above mentioned, said friction disk having a peripheral rib and said rib being positioned to engage between said contact disks. 80
24. In combination with the paper feeding mechanism of a manifolding register, a friction disk driven by said mechanism, a rewind roll for preserving as a record, a strip fed by the said feeding mechanism, and means connected to the rewind roll and comprising disks pressed toward each other, and having sides adapted to form contact members with the friction disk above mentioned, and means for adjusting the pressure on the said disks, thus varying their frictional contact with the friction disk. 85

JOHN Q. SHERMAN.
